J. A. Watrous.

Eaves Trough.

No 18,113.

Patented Sept. 1, 1857.

UNITED STATES PATENT OFFICE.

JAMES A. WATROUS, OF GREEN SPRING, OHIO.

APPARATUS FOR SUSPENDING EAVES-TROUGHS.

Specification of Letters Patent No. 18,113, dated September 1, 1857.

To all whom it may concern:

Be it known that I, JAMES A. WATROUS, of the village of Green Spring, in the county of Seneca and State of Ohio, have invented 5 a new and Improved Mode of Suspending Eaves-Troughs; and I do hereby declare that the following is a full and exact description thereof, reference being had to the accompanying drawings and to the letters of reference marked thereon.

The nature of my invention consists in a round cross-bar for the trough, to which is attached a tin loop, the ends of loop extending from the bar to any desired length 15 and passing through a slot in the end of a metal plate, to be fastened upon the roof so that the ends of the loop after passing through the slot in the metal plate, may be turned down to the right and left respectively, and clenched, so as to fasten and hold the trough in the required position.

To enable others skilled in the art to make and use my invention I will describe its construction and operation:

25 I construct my eaves trough A Figure 1 in any of the usual forms, and construct a round bar B¹, Fig. 2, of sheet tin or other metal, of any required length and flattened at each end; and in connection I loop 30 around the bar, B², a strap of tin plate or other metal D¹, Fig. 4, forming two straps above the bar B², Fig. 3, any length required. The edges of the loop around the bar, B², Fig. 3, next to the cornice G Fig.

1 to be placed at the center of the bar and 35 soldered. The bar and loop as in Fig. 3, then to be soldered to the inside edges of the eaves trough A, as represented in Fig. 1. I then provide a metal plate, C¹ Fig. 5, with a slot F in the lower end and bent up at 40 the upper end of the slot, to a horizontal position, as represented in Fig. 5.

The plate C² Fig. 1 is made fast to the roof H in any of the usual ways, or as represented in Fig. 1, in such a position 45 that the slot F in the metal plate C² will project over the end of the shingles, so as to admit the double strap D³, Fig. 6, and so that the eaves trough may be brought up to any desired point, or lowered the length 50 of the straps. The straps D³, Fig. 6, are then, as there represented, bent down to the right and left respectively and turned under the metal plate C³, so as to form a lock or 55 clench, securing the eaves trough in its place.

I do not claim the suspending of eaves troughs by bolts and nuts as patented by Woodruff; but

I claim as new and of my own invention—
The employment of a metal strap D¹ in 60 combination with the cross bar B¹ and the slotted plate C¹ for securing and readily adjusting the eaves troughs.

JAMES A. WATROUS.
